UNITED STATES PATENT OFFICE.

WILLIAM H. WALDRON, OF NEW BRUNSWICK, NEW JERSEY.

REELING-MACHINE FOR PAPER OR OTHER FABRICS.

SPECIFICATION forming part of Letters Patent No. 570,355, dated October 27, 1896.

Application filed January 16, 1896. Serial No. 575,639. (No model.)

To all whom it may concern:

Be it known that I, WILLIAM H. WALDRON, of New Brunswick, in the county of Middlesex and State of New Jersey, have invented a new and Improved Reeling-Machine for Paper or other Fabrics, of which the following is a full, clear, and exact description.

The invention relates to machines for winding paper and other fabrics, such, for instance, as shown in the Letters Patent of the United States, No. 363,024, granted to John Waldron on May 17, 1887.

The object of my invention is to provide a new and improved reeling-machine for paper and other fabrics, and arranged to automatically correct any uneven winding caused by the length of the sides or selvage of the paper or fabric to be reeled.

The invention consists principally of a winding-roll or core adapted to wind up the fabric and mounted for oblique adjustment relatively to the driving-roll.

The invention also consists of certain parts and details and combinations of the same, as will be fully described hereinafter and then pointed out in the claim.

Reference is to be had to the accompanying drawings, forming a part of this specification, in which similar characters of reference indicate corresponding parts in all the figures.

Figure 1 is a sectional side elevation of the improvement on the line 11 of Fig. 2. Fig. 2 is an end elevation of the same. Fig. 3 is an enlarged sectional plan view of the eccentric bearing for the winding-roll, and Fig. 4 is a side elevation of the same.

The improved reeling-machine is provided with a suitably-constructed frame A, in which is journaled in suitable bearings a driving-roll B, connected with other machinery for imparting a rotary motion to the said driving-roll, so as to rotate the winding-roll C, arranged directly above the driving-roll, and on which the paper or other fabric is wound. The winding-roll or core C is journaled at one end in a bearing D, fitted to slide vertically in the slotted standard A' of the frame A, the other end of said core or winding-roll being journaled in a bearing D', like-

wise fitted to slide vertically in a slotted standard A'. The bearing D' is formed with an eccentric bore for the reception of the end C' of the winding-roll shaft, so that when the bearing is turned said winding-roll can be thrown obliquely relatively to the driving-roll B, so that any inequality in the paper or fabric is compensated for during the winding up of the same on the roll C, so that said fabric or paper is evenly wound up on said roll.

In order to conveniently change the position of the bearing D', I provide the latter with a suitable handle D² under the control of the operator, to enable the latter to change the position of the winding-roll relatively to the driving-roll whenever desired. It is understood that as the bearings D D' are free to slide vertically any adjustment of the eccentrically-mounted end C' of the winding-roll does not affect the horizontal position of the roll, but the axis of the winding-roll stands obliquely in a horizontal direction relatively to the vertical plane passing through the axis of the driving-roll B. It is understood that this movement in a horizontal direction of the winding-roll C is permissible, owing to the journal of the roll C in the bearing D, it being sufficiently loose for the purpose. The winding-roll C is weighted in the usual manner by a weight E, connected by rods E' with saddles E² on the said winding-roll.

Having thus fully described my invention, I claim as new and desire to secure by Letters Patent—

In a reeling-machine, the combination with a driving-roll, of a winding-roll, sliding bearings in which said winding-roll is journaled to move toward and from the driving-roll, one of the bearings receiving the journal of the winding-roll eccentrically, and means for turning said bearing for shifting said end of the winding-roll transversely to the direction of the sideways, substantially as described.

WILLIAM H. WALDRON.
